UNITED STATES PATENT OFFICE.

FRANCIS J. ROBINSON, OF AURORA, ONTARIO, CANADA.

STRETCHER AND DRIER FOR HIDES AND LEATHER.

1,392,968.

Specification of Letters Patent. Patented Oct. 11, 1921.

Application filed December 8, 1920. Serial No. 429,094.

To all whom it may concern:

Be it known that I, FRANCIS J. ROBINSON, of Aurora, in the county of York, Province of Ontario, Canada, a subject of the King of Great Britain, have invented certain new and useful Improvements in Stretchers and Driers for Hides and Leather, of which the following is a specification.

This invention relates to devices used for stretching and drying hides and leather, raw or tanned. Several of these devices have been devised at different times, but so far none which will satisfactorily do the work as their construction has not been sufficiently strong to withstand the strain of the leather being stretched or dried thereon.

My object therefore is to devise a construction for the purpose which will be sufficiently strong to stand up under all ordinary conditions, which will not be too expensive to construct, and which may be repaired at a minimum of expense.

I attain my object by means of the constructions hereinafter described and illustrated in the accompanying drawings in which—

Figure 1 is an elevation of my improved stretcher, partly in section, part of a hide being shown in position thereon;

Fig. 2 an end elevation of the same, partly in section; and

Fig. 3 a sectional detail of one of the clamp hooks.

In the drawings like numerals of reference indicate corresponding parts in the different figures.

1 is a frame, preferably of square or rectangular shape. This frame is provided with a plurality of longitudinal braces 2 parallel to the sides of the frame. The ends of these longitudinal braces will be provided with tenons to fit into mortises formed in the ends of the frame, as indicated in dotted lines.

3 are transverse braces extending between the longitudinal braces and between the longitudinal braces and the sides. These transverse braces will also be provided with tenoned ends to fit into mortises formed in the longitudinal braces and sides of the frame.

It will be noted that the transverse and longitudinal braces are of exactly the same thickness as the inner edge of the frame.

Corner braces 4 are provided which are secured to the frame by bolts 5 passing through the same.

To each side of the frame I secure a stretching or drying surface. As the wire netting used in the prior constructions has many disadvantages, for example, that the individual wires will give when a piece of leather is being stretched on the device, and further that there is more or less danger of "dints" being formed in the leather through the surface not being perfectly flat, I prefer to use perforated sheet metal. While I may use a single sheet of sufficient size to cover the entire frame, to save material I prefer to cover each side of the frame with two large pieces 6 and to fill in the space at each end with a smaller piece 7, leaving an uncovered space at the center of the device. I show the different sections of the perforated surface as being overlapped, but it will be understood that I may simply have their edges abutting one another.

It will be noted on reference to Fig. 2 that the outer edge of the frame is of greater thickness than the inner edge, and that the perforated sheets 6 and 7 only extend to the inside of this thicker portion. I therefore secure the edges of the pieces 6 and 7 to the frame by means of filling pieces 8, which are secured to the frame by means of nails passing through the perforated metal.

It is preferable, particularly, when the stretching surface is formed of a plurality of pieces, to secure the same to the braces, as, for example, by nails 9, as otherwise the perforated surface would be liable to buckle, and it is one of the important features of my invention that the perforated surface should be absolutely flat and not allowed to bend inwardly or outwardly.

Clamp hooks 10 are provided adapted to be engaged with the corners or sides of a hide or piece of leather and adapted to hook into the apertures in the perforated surface. Any suitable clamp hook may be employed, but I prefer to use a hook constructed substantially as shown in the drawings. Each clamp hook is formed with a fixed jaw 11 above which is pivoted the movable jaw 12, which movable jaw is operated by means of a cam lever fulcrumed on lugs 14 extending up from the sides of the fixed jaw 11. The movable jaw is formed with a hooked lug 15 engageable by the cam lever to lift the movable jaw to enable the jaws to be engaged with the hide, which is subsequently secured by pressing down the cam lever. A

ring 16 is connected to the rear of the fixed jaw, which ring has a downwardly directed extension 17 adapted to act as a hook to engage in the apertures in the perforated sheets. In Fig. 3 the clamp hook is shown in full lines with the jaws open and in dotted lines with the jaws closed.

The mode of operation is to secure clamps to the corners or other projections of the hide and then to engage the hooks 17 in any suitable apertures of the metallic sheet to apply the desired stretching tension to the hide.

As a hide or piece of leather may be secured on each side of my device, there will be less danger of the same warping when in use, and as there are no projections of any kind on either surface, there will be no danger of "dints" or "bulges" being formed in the leather.

As the frames in actual practice will be quite large, a considerable saving will be made by omitting the covering at the center, and further, should any section of perforated metal become damaged, it will only be necessary to replace that particular section instead of a whole sheet.

From the above description it will be seen that I have devised a stretching and drying

device which will satisfactorily attain the objects of my invention as set out in the preamble of this specification.

What I claim as my invention is:—

1. In a leather stretcher, the combination of a rectangular frame provided with longitudinal and transverse braces, the outer edge of the frame being of greater thickness than its inner edge and the braces being of substantially the same thickness as the inner edge of the frame; perforated sheet metal at each side of the frame; and filling pieces securing the perforated sheet metal to the frame.

2. In a leather stretcher, the combination of a rectangular frame provided with longitudinal and transverse braces, the outer edge of the frame being of greater thickness than its inner edge and the braces being of substantially the same thickness as the inner edge of the frame; perforated sheet metal at each side of the frame; filling pieces securing the perforated sheet metal to the frame; and means securing the sheet metal to the braces.

Signed at Twp. of Vaughan, Co. of York, 55 Prov. of Ont., this 27th day of Nov., 1920.

FRANCIS J. ROBINSON.
